UNITED STATES PATENT OFFICE.

HOWARD O. McMILLAN, OF MINNEAPOLIS, MINNESOTA.

SHORE AND TRENCH BRACE.

Application filed June 29, 1925. Serial No. 40,273.

To all whom it may concern:

Be it known that I, HOWARD O. McMILLAN, a citizen of the United States, residing at Minneapolis, in the county of Hennepin 5 and State of Minnesota, have invented certain new and useful Improvements in Shore and Trench Braces; and I do hereby declare the following to be a full, clear, and exact description of the invention, such as will 10 enable others skilled in the art to which it appertains to make and use the same.

This invention relates to a timber support or shore such as commonly used in building construction. It is desirable to have a shore 15 which firmly supports and holds the timber and it is very desirable to have a shore which can be adjusted so that the timber supporting part can be raised any distance desired relatively to the standard.

It is an object of this invention, therefore, 20 to provide a shore comprising a standard and a timber supporting member movable relatively thereto, together with means for moving said timber supporting member any 25 distance desired along the standard, which shore also has a high degree of utility when used as a trench brace.

It is a further object of the invention to 30 provide a shore, as set forth in the preceding paragraph, in which the standard also has means adjacent its top for clamping the supported timber.

It is still another object of the invention to 35 provide a shore having a standard with a timber supporting bracket slideable thereon, together with means adapted to pass transversely through the bracket and standard for raising and holding said bracket in the desired position.

It is still another object of the invention to 40 provide a shore, as set forth in the preceding paragraph, in which the standard has a series of spaced slots therein and said bracket has a plurality of slots therethrough 45 spaced a different distance apart than the slots in said standard, said means comprising a pair of wedges adapted to be driven through the slots in said bracket and standard and relatively move said parts.

These and other objects and advantages 50 of the invention will be fully set forth in the following description made in connection with the accompanying drawings in which like reference characters refer to the 55 same parts throughout the different views, and in which,

Fig. 1 is a view in front elevation of the shore showing a portion of a timber supported thereby;

Fig. 2 is a view in side elevation, as seen 60 from the right of Fig. 1;

Fig. 3 is a top plan view of the device;

Fig. 4 is a transverse section on the line 4—4 of Fig. 2 as indicated by the arrows;

Fig. 5 is a view similar to Fig. 3, showing 65 a modification; and

Fig. 6 is a view in side elevation of Fig. 5.

Referring to the drawings, a shore is shown comprising a standard 5. While this standard may be made of various forms, or 70 shapes, in the embodiment of the invention illustrated, the same is shown as formed of a T-bar having a lower end extending substantially at right angles to its length to which is connected a foot 5^a comprising a flat plate 75 having upstanding ears 5^b embracing the main arm or web 5^c of the standard 5 and being connected thereto by a suitable rivet, one side of the ears 5^b being disposed adjacent the cross arms 5^d of the standard. A 80 timber supporting bracket 6 is provided having a main portion with a T-shaped slot 6^a therein adapted to fit over the standard 5 so that the bracket is slideable thereon and has flat sides embracing the main arm or 85 web 5^c of the standard. The bracket 6 has a plate 6^b extending outwardly of its top substantially at right angles to the face of the cross arms 5^d of the standard, which plate has an upwardly projecting fin 6^c 90 at its outer edge. A central triangular rib 6^d is shown as connecting the plate 6^b to the main portion of the bracket and said plate 6^b has a plurality of holes 6^e therethrough adapted to receive nails or spikes 7 driven 95 therethrough upwardly into the bottom of the timber 9 which is supported upon plate 6^b. The main web 5^c of the standard 5 is provided with a plurality of elongated spaced slots 5^e extending therethrough shown 100 as rectangular in shape and aligned longitudinally of said standard. The sides of bracket 6 at each side of web 5^c are provided with a plurality of similarly shaped slots 6^f centrally aligned with the slots 5^e but spaced a 105 different distance apart than the slots 5^e. In the embodiment of the invention illustrated, the slots 6^f are shown as spaced farther apart than the slots 5^e. A pair of wedges 8 are provided adapted to extend through the slots 5^e and 6^f, as clearly shown in Figs. 1, 2 and 110 4, said wedges being shown as having small

square apertures 8^a extending therethrough adjacent their longer ends. Pairs of lugs 6^f and 6^g are provided at one side of brackets 6 between which wedges 8 move, the lugs 6^f being threaded to receive set screws 12. The holes 8^a are made to fit over the heads of screws 12 so that the wedges 8 constitute wrenches to turn said screws. The standard 5 has secured thereto adjacent its top, a yoke 10 and while this yoke may be variously formed, in the embodiment of the invention illustrated, it is shown as formed of a flat bar having its ends disposed at each side of web 5^c and riveted thereto, the sides of said yoke extending outwardly at each side of said web closely adjacent the cross arms 5^a and parallel to and beyond the latter. The sides of the yoke are then extended outwardly parallel to each other and at right angles to the front of the standard 5, the sides being joined by an end portion 10^a extending at an acute angle to said sides. The sides of the yoke 10 adjacent the end 10^a are provided with aligned elongated slots 10^b adapted to receive a flat wedge member 11, said wedge member being shown as having a small aperture 11^a therethrough adjacent its wide end and having pins 11^b projecting at each side adjacent its center. The wedges 11 also have their narrow end bent at right angles to form a tongue 11^c.

In the modification shown in Fig. 6 a different form of yoke is shown to be used in place of yoke 10. Angle pieces 13 are provided illustrated as made from a short piece of flat bar bent at right angles, said members being disposed against opposite sides of web 5^c and riveted thereto so that the bent portions project outwardly and oppositely at right angles to said web. Strips or plates 14 and 15 also made from flat bars are riveted at either side of the members 13 and project forwardly at both sides of the front of the standard 5, plates 14 and 15 being secured at their outer ends to a strip or plate 16 riveted between the plates 14 and extending to and riveted between the plates 15, said plates 16 extending at an angle to the front face of standard 5. The plates 14 and 15 also extend at each side of the timber 9 and the wedge 11 can be driven into place between plates 14 and 15 and with its inclined side engaging the edge of plate 16. The other side of the wedge 11 engages the face of timber 9 so that said timber is tightly clamped in position against the standard 5.

In the use of the device as a shore the same will be brought adjacent the timber 9 to be supported and the flat bottom end of said timber will be engaged with the top of plate 6^b, the timber being disposed within and held from outward movement at its lower end by the fin 6^c. The timber can be held against lateral movement by driving

the spikes 7 into the bottom thereof through the holes 6^e. It is unnecessary, therefore, to fit the bottom of the timber between any parts or flanges at its sides. The timber 9 will pass through the yoke 10. In order to support the bracket 6, one of the wedges 8 will pass through a pair of slots 6^f in the bracket and through one of the slots 5^c in the standard. If it is desired to raise the timber 9 the wedge 8 will be driven through the bracket 6 and web 5^c of the standard and the successive movements of the wedge resulting from the blows thereon will gradually raise the bracket 6 and timber 9. When the wedge 8 has been driven in place to its widest part, another slot 5^c will be brought into partial alinement with the other pair of slots 6^f and the other wedge 8 can then be inserted through these partially alined slots and driven through the brackets and standard. The bracket 6 will be raised as this wedge is successively driven into place and when the wide part of the wedge has been driven into the bracket 6 another slot 5^c will be partially brought into alinement with the first mentioned pair of slots 6^f so that the wedge first used can again be inserted and driven into place. It is thus possible by the successive use of the wedges 8 to raise the bracket 6 and move the same along the standard 5 any desired distance. The bracket 6 can be moved throughout substantially the whole length of the standard 5. The bracket 6 can be raised with the rod or timber 9 thereon and it is unnecessary to make any adjustment of the bracket 6 and standard 5 or to change the relative position before using the next wedge 8. The bracket 6 can be continuously moved by the successive use of the wedges without any retrograde movement of the bracket 6. The wedges 8 not only act to raise the bracket means but also form a holding means for holding the same in desired position. While the wedges 8 bind against the ends of slots in bracket 8 and web 5^c, and are securely held in place, the set screws 12 are provided by means of which the wedges can be securely locked in position, if desired. The set screws 12 can readily be turned by using one of the wedges 8 as a wrench. After the timber 9 is brought to the desired position, the wedge 11 is inserted into slots 10^b with its inclined end in engagement with the inclined end 10^a of the yoke 10 and the wedge then driven tightly into position. The wedge 11 will act to firmly clamp the timber 9 between the same and the front of standard 5 so that the timber is held very securely in position. The timber does not have to be dressed to exactly fit the yoke. Pins 11^b and tongues 11^c prevent the wedges 11 from being removed from their respective yokes so that said wedges are always in position ready for operation.

The operation of the form of yoke shown in Fig. 5 is similar to that of yoke 10 and it is thought no further description thereof will be necessary.

5 When the device is used as a trench brace the same will extend transversely across the trench at right angles to the sides thereof, the brace 5^a will be placed flat against a board at one side of the trench. A block 10 similar to the short length of the timber 9 illustrated will now be placed through the yoke 10 and against the plate 6^b, said block being of sufficient length to extend beyond the yoke 10. The outer end of this block 15 can now be engaged with a board at the side of the trench opposite that at which the brace 5^a is disposed. The block can then be moved by the bracket 6 by the use of the wedges, as above described. The sides of 20 the trench can thus be effectively braced and the boards at the side of the trench can be pressed apart as is desired.

From the above description it is seen that applicant has provided a very simple and 25 efficient adjustable shore and trench brace. When used as a shore, the device, as described, can be easily and quickly placed in position and the timber supported thereon can be raised any amount, as desired, without any re-setting of the bracket 6. The 30 device is easily and inexpensively made and can be made very rugged so that it will be quite durable.

It will, of course, be understood, that various 35 changes may be made in the form, details, arrangement and proportions of the parts without departing from the scope of applicant's invention, which, generally stated, consists in a device capable of carrying 40 out the objects above set forth, in the novel parts and combinations of parts disclosed and defined in the appended claims.

What is claimed is:

1. A shore comprising a standard, a timber-supporting bracket slidable thereon, and members adapted to pass through said standard and bracket for successively moving said bracket upward along said standard.
2. A shore comprising a standard, a timber-supporting bracket slidable thereon, said standard having a series of spaced elongated slots therethrough and said bracket hav-

ing a series of elongated slots therethrough spaced different distances apart than said slots in said standard, and a pair of wedges 55 adapted to be driven through partially alined slots in said standard and bracket for moving said bracket along said standard and holding the same in position.

3. The structure set forth in claim 2, said 60 bracket having lugs thereon and set screws disposed in said lugs adapted to be tightened against said wedges to hold the same in proper position.

4. A shore comprising a standard, a timber-supporting bracket slidable thereon, said standard having a series of spaced elongated slots therethrough throughout substantially its whole extent and said bracket having a 65 series of elongated slots therethrough spaced 70 different distances apart than said slots in said standard, a pair of wedges adapted to be driven through partially alined slots in said standard and bracket for moving said bracket along said standard and holding the 75 same in position, and means for locking said wedges in position.

5. A shore and trench brace comprising a standard, a timber supporting bracket slidable thereon, a plurality of members 80 adapted to pass through said standard and bracket for successively moving said bracket upward along said standard, and timber clamping means at the top of said standard.

6. A shore and trench brace comprising 85 a standard, a bracket slidable thereon having a timber supporting surface extending substantially at right angles to said standard, means for retaining a timber on said bracket and members adapted to pass 90 through said standard and bracket for successively moving said bracket upward along said standard.

7. A shore comprising a standard, a timber supporting bracket slidable thereon, a 95 plurality of members adapted to pass through said standard and bracket for successively moving said bracket upward along said standard, a timber embracing yoke adjacent the top of said standard, and clamp- 100 ing means for connection with said yoke for clamping a timber therein.

In testimony whereof I affix my signature.

HOWARD O. McMILLAN.
